SAFETY PILOT LIGHT

Frank A. Gauger, Milwaukee, Wis., assignor to
Milwaukee Gas Specialty Company, a corpora-
tion of Wisconsin

Original application April 5, 1930, Serial No.
441,836. Divided and this application Febru-
ary 6, 1933, Serial No. 655,418

5 Claims. (Cl. 158—117.1)

This invention relates to a safety pilot light.

This application is a division of my copending application Ser. No. 441,836, filed Apr. 5, 1930, for Safety pilot light.

Objects of this invention are to provide a novel form of safety pilot light which may be mounted wholly within a combustion chamber, such, for example, as the combustion chamber of a furnace or other apparatus, which is so made that it will 10 not respond to the general temperature or the radiated heat in the combustion chamber, but will respond only to the heat generated by the pilot light itself, such pilot light being so made and associated with a thermostatic member that 15 in the specific construction a portion of the flame of the pilot light plays directly upon the thermostatic member.

Further objects are to provide a novel form of 20 pilot light, combined as a unit with a thermostatic member, which is so constructed that the thermostatic member is directly carried by the pilot light and forms a unitary portion therewith, in which the supporting structure for the combined pilot light and thermostatic member 25 is in reality the supply pipe and supply nozzle for the pilot light, and in which the construction is such that the entire pilot light and thermostatic control device may be bodily lifted from the supply pipe and supply nozzle, for repair or inspection, in a very simple and easy manner.

Further objects are to provide a novel form of 30 safety pilot light in which the thermostatic member is quickly responsive, and is preferably so made that a positive stop is provided for arresting the motion of the movable portion of such thermostatic member at one point in its travel to thus prevent excessive pressure being exerted upon the control member, and to so construct the thermostatic member and so associate it with the 35 pilot light that the maximum speed of response is obtained.

Further objects are to provide a novel form of 40 safety pilot light which is mounted, as pointed out above, wholly within the combustion chamber, but which, nevertheless, operates a control member located outside of the heated zone of the combustion chamber and protected from excessive heat, and preferably located within the incoming stream of secondary air, so that it is 45 maintained in a fairly cool condition at all times and irrespective of the temperature within the combustion chamber.

In greater detail, objects of this invention are 50 to provide a safety pilot light in which a tubular member, provided with a supply nozzle, supports

an integral structure comprising the balanced U-tube pilot light, the thermostatic member, and the control member operated thereby, and to so associate these parts that there is an imperfect thermal conductivity path between the pilot light and the supply nozzle, so that the supply nozzle does not become excessively heated, thereby avoiding carbonization and choking of such supply nozzle.

Further objects are to provide a construction 10 for a safety pilot light which may be manufactured with the utmost ease, which is extremely simple, which is easy to position and remove, which is rugged, and which is not likely to get out of order.

Embodiments of the invention are shown in the accompanying drawings, in which:

Figure 1 is a sectional view through a portion 20 of a furnace and through a part of the safety pilot light.

Figure 2 is an enlarged sectional view on the line 2—2 of Figure 1.

Figure 3 is an enlarged sectional view on the line 3—3 of Figure 1.

Figure 4 is a view corresponding to Figure 1 25 showing a different form of the apparatus.

Figure 5 is an enlarged sectional view on the line 5—5 of Figure 4.

Before entering the detailed discussion of this invention, it is to be noted that the pilot light is 30 adapted to be positioned wholly within the combustion chamber, and is provided with a control member which is located outside of the combustion chamber, or at all events, outside of the heated zone of such chamber, and that the control member may be either an electrical control member or may be so constructed that it controls through the medium of gas pressure, or in a similar manner.

Referring to Figures 1 to 3 which show the first 35 form of the invention, it is to be noted that a gas furnace has been indicated as provided with a casing 1 provided with a transverse portion 2, and forming a combustion chamber 3. A main burner 4 is located within the combustion chamber and is supplied from the main gas supply manifold 5, a valve 6 being provided between the manifold and the mixing tube 7 of the burner. The secondary air enters the space indicated at 8 and passes upwardly through the duct provided 40 by the auxiliary casing 9.

It is to be noted that a branch supply pipe 10 extends downwardly from the manifold 5 and is provided with a control valve 11. This branch pipe extends upwardly, as indicated at 12, and 45

provides a support for the safety pilot light. The portion 12 preferably is carried by a shouldered fitting 13, and is provided with a small supply nozzle 14 at its upper end.

- 5 The safety pilot light comprises a U-burner having two main passageways 15 and 16 which communicate by way of the intermediate passageway 17. All of these passageways are formed in an integral casting 18 and it is preferable to provide a plurality of openings 19, which are in reality the openings at which the flames are formed. Preferably one opening 19' is on the upper side of the casting of the U-burner, as shown in Figure 1, and is located practically directly beneath the curved portion of the thermostatic member 20. This thermostatic member is locked to the casting 18 by means of a bolt 21 or other suitable member. This bolt has its head located below the free arm of the thermostatic member 20 and provides a stop for such free arm to limit its downward motion. The free arm is provided with a substantially non-expanding metal projecting arm 22 which is riveted thereto or otherwise secured. This arm 22 is provided with an adjusting screw or contact member 23, which, when in adjusted position, is locked by means of the lock nut 24.

Returning to the U-burner of the safety pilot light, it will be seen that the casting 18 is bored and threaded to receive the Venturi insert tube 25 and the insert bushing 26, which latter receives the supply nozzle 14 and thus accurately aligns the nozzle with the Venturi tube 25. As a matter of fact, the holes for the Venturi tube 25 and the bushing 26 may be readily bored out in the casing as they are in alignment, and thus it is a simple matter to bore and thread such holes.

At this point it is to be particularly noted that there is only a sliding fit, which is fairly loose, 40 between the supply nozzle 14 and the bushing 26. Consequently the thermal conductivity between the casting 18 of the U-burner and the supply nozzle 14 is very poor. The result of this construction is that the supply nozzle is only 45 slightly heated even when the apparatus is in continuous operation, and consequently carbonization and choking of the nozzle cannot occur.

The casting 18 is rigidly carried by a sleeve or tube 27 which forms an integral portion thereof, 50 and whose lower end is threaded into a casing 28 also formed as a casting. This casing 28 is provided with an apertured lip 29, which is slidably carried by the supply pipe 12, preferably fitting over the cylindrical portion of the fitting 13 and 55 resting upon the lower shouldered portion of such fitting. The construction is such, therefore, that the U-burner of the safety pilot light is in reality carried by the supply pipe, the upper end of the safety pilot light fitting over the supply nozzle 60 and the lower end being slidably carried and supported by the supply pipe.

Preferably the lower portion of the casing 28 is 65 closed by means of an insulating bottom plate 30. This insulating bottom plate 30 carries a stationary contact member 31 and a U-shaped, movable, spring contact member 32. The movable contact member 32 is most clearly shown in Figure 3, and it will be seen that such member is provided with a lip or ear 33 underhanging the stationary contact 31 and with a lip or ear 34', which is readily fastened to the insulating base plate 30. Suitable binding posts 34 are connected to the contacts and also are connected to the conductors of a cable 35, see Figures 1 and 2. The 70 cable 35 extends to the main control valve in

the usual manner, so that when the contacts are closed, the valve is permitted to operate, but when the contacts are opened, due to the action of the thermostatic member, the main valve is prevented from opening.

5 The means for operatively connecting the thermostatic member and the movable contact may consist merely of a small rod 36 which extends directly downwardly from the adjustable contact or member 23 carried by the arm 22 of the thermostatic member and bearing at its lower end upon the spring or movable contact member 32, see Figure 1. This rod may be provided with a slightly enlarged head 37 at its lower end, and it is preferable to form this head of insulating 15 material to thus electrically insulate the movable contact member from the metal rod.

From actual trials it has been found that there is a tendency for particles of dust to be drawn 20 downwardly into the passageway 16. Obviously, irrespective of the minuteness of these particles, they will ultimately somewhat clog or pack around the rod 36 if the rod is not protected therefrom. Consequently, a small, protecting sleeve or tube 38 loosely surrounds the rod 36 and is preferably 25 threaded into the main casting 18 of the U-burner of the pilot light, as shown in Figure 1. This sleeve 38 is relatively small and does not close the passageway 16. Consequently air can flow 30 between such tube 38 and the walls of the passageway 16, and thus provide an adequate supply for the U-burner of the pilot light. However, inasmuch as the tube 38 projects upwardly a considerable distance, preferably to the top of the casting 18, it is clear that the rod is guarded from 35 accumulation of dust particles entrained with the air.

From the description thus far given, it is apparent that a balanced U-tube safety pilot light has been provided by this invention which is so 40 made that it may be wholly mounted within the combustion chamber of a furnace or similar device, and which cannot be extinguished by explosions or sudden variations of pressure occurring within such combustion chamber.

45 It is also apparent that very simple and easily constructed control means are provided and associated with the safety pilot light, and that excessive displacement of the elements of this control member is prevented by the manner in which 50 the thermostatic apparatus is constructed, as previously described.

55 Although the operation is apparent from the previous description, it is believed a brief statement thereof is desirable.

When the pilot light is in operation, the thermostatic member 20 is heated and the arm 22 is moved upwardly, thus allowing the rod 36 to move 60 upwardly and allowing closing of the contacts. As previously stated, any explosion, due to lighting or extinguishing of the main burner, produces the same pressure upon the opposite ends of the U-shaped burner of the pilot light and does not, therefore, tend to extinguish such pilot light. The thermostatic member is so constructed that 65 as long as it is heated, preferably directly by the pilot light, it will maintain the contacts closed. However, if the pilot light is extinguished for any reason, the thermostatic member then moves the arm 22 downwardly, forcing the rod 36 downwardly, and opens the contacts. This, in accordance with the well known practice, opens the circuit of the main supply valve and prevents supply of fuel to the main burner.

70 The form of the invention shown in Figure 4 75

is substantially the same as that shown in Figure 1, with, however, the exception that the control member is differently constructed. This control member operates a control valve by gas pressure 5 in a well known manner.

The control member, in this second form of the invention, is the only differently constructed portion of the apparatus from that previously described, and consequently such control member 10 alone need be described.

This control member consists of a fitting 39 which carries a valve seat 40 adapted to cooperate with a ball valve 41. This ball valve is urged towards closed position by means of the helical compression spring 42, and is forced open by 15 means of the rod 36 previously described. The lower portion of the fitting 39 is closed by a plug 43 screwed thereto and carrying the compression spring 42. The supply pipe 12, similar to 20 that previously described, is provided with a fitting 44, which replaces the fitting 13, see Figure 1. The fitting 44 and the fitting 39 are provided with flat faces, which may take any shape. In Figure 25 4 the face of the fitting 44 is shown. These faces are drawn together, and consequently the fittings 44 and 39 are joined by means of bolts or screws 45, preferably a washer 46 of paper, fiber, or similar material being interposed between such faces to insure a gas-tight joint.

30 A control pipe 47 leads outwardly to the control valve (not shown) from the fitting 39 and communicates with the space above the valve 41 by means of a small duct 48. The interior of the supply pipe 12 communicates with the space below 35 the valve 41 by means of a small duct 49. It is clear, therefore, that when the valve 41 is seated, which would correspond to the condition when the pilot light is lighted, no gas pressure is transmitted to the pipe 47 past the control member, and, consequently, the control valve for the main burner is allowed to operate, as required, in the usual and well known manner. However, when the valve 41 40 is displaced by the thermostatic member, gas pressure is communicated to the pipe 47 and the main control valve (not shown) is prevented from operating, and, consequently, no gas can pass to the main burner.

It is to be noted that the pipe 50, which connects with the supply pipe 12, is to be connected 50 to the supply mains ahead of the automatic control valve (not shown) for the main burner, in the usual manner.

It is to be noted particularly that no stuffing box or packing is required for the rod 36, as any 55 gas that leaks past this rod in the normal operation of the apparatus is entrained with the incoming air for the pilot burner and consequently is consumed in the pilot burner. The gas passing the rod 36 is drawn through the port 51 and is thereby carried along with the mixture to the 60 pilot burner.

It will be seen that means are provided intermediate the control member, whether it takes the form of the electric contacts shown in Figure 1 or the valve 41 shown in Figure 4, and the thermostatic member whereby the effect of the length of the rod 36 may be adjusted to determine the point at which the device will operate.

It will be seen that both forms of the invention 70 are substantially the same, the differences consisting only in the types of control members employed.

It is to be noted particularly that the construction of the apparatus is such that the safety pilot light can be mounted wholly within the casing 75

of the combustion chamber, and that this safety pilot light is not caused to operate by the general temperature or heat within the combustion chamber, but is responsive only to the heat generated by the pilot light.

It will also be seen that a very simple type of safety pilot light has been provided in each form of the invention which is easy to construct, which is substantially foolproof, which is positive in its operation, and which is truly reliable.

Although this invention has been described in considerable detail, it is to be understood that such description is intended as illustrative rather than limiting, as the invention may be variously embodied and is to be interpreted as claimed.

I claim:

1. A unitary pilot light and thermostatic pilot device comprising a main burner, a U-shaped pilot light for said main burner constituting a Bunsen burner, a fuel supply pipe for 20 said pilot light, a thermostatic member carried by said pilot light and responsive thereto, a control device mounted as a rigid unit with said pilot light and operated by said thermostatic member, said pilot light, said thermostatic member 25 and said control device forming a unitary structure supported from said fuel supply pipe and readily removable therefrom by a sliding motion longitudinally of said supply pipe.

2. A pilot light comprising a supporting fuel 20 supply member provided with a fuel nozzle, a U-tube body portion, one of its main arms being an air inlet and the other main arm being a mixture outlet, said fuel supply member forming the support for said body portion and said fuel nozzle 35 having poor thermal connection with said body portion to prevent carbonization at the nozzle, and a thermostatic member carried by the said main arm forming the mixture outlet, said thermostatic member being responsive to said pilot 40 light, and control means actuated by said thermostatic member.

3. A pilot light having a body portion provided with an air inlet and a fuel outlet, a fuel supply pipe having a nozzle opening into said body portion, said fuel supply pipe extending downwardly from the nozzle, supporting means rigidly connected with said body portion and extending downwardly from said body portion, said means being supported by said fuel supply pipe at a 50 point remote from and below said nozzle and supporting said body portion, a thermostatic member carried by and responsive to said pilot light, and control means including means connecting the same to said thermostatic member and spaced 55 downwardly therefrom and supported as a unit from said fuel supply pipe with said pilot light.

4. A pilot light having a body portion provided with an air inlet and a fuel outlet, said fuel outlet constituting an extension projecting laterally 60 from said air inlet, and said air inlet and said fuel outlet forming a U-burner, a fuel supply pipe having a nozzle opening into said body portion, said fuel supply pipe extending downwardly from the nozzle, supporting means rigidly connected with said body portion and extending downwardly from said body portion, said means being removably supported by said fuel supply pipe and supporting said body portion at a point remote 65 from and below said nozzle, a thermostatic member carried by the laterally projecting extension of said pilot light and responsive to said pilot light, and a control device supported from said body portion at a point spaced downwardly from 70

said pilot light, said control device being operatively connected to said thermostatic member.

5. In a device of the class described, a casing, a main burner located within said casing, a fuel supply, a fuel standard nozzle connected to said fuel supply, a U-tube Bunsen pilot light positioned within said casing and drawing its primary and secondary air from within said casing only, a

thermostatic member carried by said pilot light and responsive thereto, and a control device carried as a unit with said pilot light, said pilot light being detachably supported by said fuel standard nozzle and being readily lifted therefrom as a unit with said control device without disturbing the adjustment of said thermostatic member.

FRANK A. GAUGER.
